UNITED STATES PATENT OFFICE

HASCAL A. HOGEL, OF BOSTON, MASSACHUSETTS.

COMPRESSED-AIR WATER-ELEVATOR.

1,042,227.

Specification of Letters Patent.

Patented Oct. 22, 1912.

Application filed January 9, 1909, Serial No. 471,472. Renewed March 19, 1912. Serial No. 684,812.

To all whom it may concern:

Be it known that I, HASCAL A. HOGEL, a citizen of the United States, residing at Boston, in the county of Suffolk and State of Massachusetts, have invented certain new and useful Improvements in Compressed-Air Water-Elevators: and I do hereby declare the following to be a full, clear, and exact description of the invention, such as will enable others skilled in the art to which it appertains to make and use the same.

This invention relates to compressed air water elevators especially adapted for mines, and has for its object the production of a pump which will be comparatively inexpensive to construct; will be certain in action when the water discharge pipe is lengthened, or becomes clogged from any cause; or when the load is otherwise increased; one that will not be destroyed or rendered inefficient by the acids or sand of the mine waters; and will be capable of a continuous operation, although the air pressure may vary within wide limits while the drills are working.

With these and other objects in view the invention consists in the details of construction and novel combination of parts more fully hereinafter disclosed and particularly pointed out in the claims.

Referring to the accompanying drawings forming a part of this specification in which like numerals refer to like parts in all the views:—Figure 1, is an elevational view partly in section of one form of the invention. Fig. 2, a detail view of one of the check valves. Fig. 3, a detail view of the rotating parts of the air engine. Fig. 4, a sectional detail of a modification. Fig. 5, an elevational view partly in section of another form of the invention, and Fig. 6, a detail view of a still further modified form of water elevating engine.

The principle of the well known Pohle air lift pump in which air is conducted through a pipe to the bottom of a well and is then discharged upward into a water discharge pipe is now well understood, and it is recognized that in order for pumps of this nature to become effective it is essential that the discharge pipe be submerged in the water to be lifted at least a distance equal to 66% of the height it is desired to raise such water. This condition renders such pumps wholly unsuited for mines, where the lift is great and the depth of water very small in com-

parison. Again, pumps have heretofore been proposed to utilize Dr. Pohle's principle where the lift is great and the water in the mine comparatively shallow, by providing the discharge pipe and lower water receiving chambers with check valves; there being a supply of air under a constant pressure intermittently applied. But in all such devices, if the pressure of the air supply greatly varies either a large part of the air and power is wasted, or else the pump refuses to operate. Besides, if the water discharge pipe is lengthened in order to deliver the water at a higher level, or if it gets clogged from any cause, as for example by the slimes, sand and other foreign material that must go up with the water, such pumps will again fail to work. Likewise, it often happens that the sumps from which the water is to be drawn have to be made in solid rock, and such pumps require a considerable excavation to provide a suitable reservoir in which their suction pipes may be accommodated. Furthermore, the suction valves often become clogged and cut with the sand and other material carried by the mine waters; and although such pumps may operate satisfactorily for a time, they give trouble in the end.

All the above objections are overcome by my construction, as will now appear.

Referring to Fig. 1, 1 represents any suitable air compressor, preferably of a rotary type; 2 a pipe of a suitable cross sectional area conducting air to the water to be lifted; 3 a valve controlling the same, and 4 a pipe supplying air to the drills, or to any other place of use. The air pipe 2, leads to the engine casing 5, in which are mounted the rotary vanes 6, or other suitable rotor; and from said casing leads the air discharge pipe 7, as shown. This air discharge pipe delivers into the water discharge pipe 8, preferably above the valve 9, although in some cases it may deliver the air from the engine into said pipe 8 below said valve, if desired. The ends 10 of the vanes 6 abut against the inner end wall of the casing 5, as shown, while rigid with the other ends of said vanes is the disk or diaphragm 12, which separates the engine chamber in two parts, one for air and one for water, as shown. In the water compartment are located the vanes 13, or other rotor, rigid with the vanes 6, and 14 represents a water inlet for said compartment. The rotor is provided with large

bearings 15 fitting the casing 5, as shown, and said water compartment is deepened at 16 for a purpose that will appear. So far as now disclosed, if air is admitted through 5 the valve 3, the rotor of the engine will turn at a speed depending upon the pressure of the air entering the chamber 5, and water will be forced up into the pipe 8, a distance depending upon said speed. If the speed 10 is considerable, the rotor will act to displace the water as it flows in through the opening 14, creating a tendency for the water to rush in behind the same as is well known; and as the parts do not fit tight, any air that 15 leaks past the diaphragm 12 will be carried around with said rotor and escape up into the pipe 8 behind the water. Ordinarily, air escaping into the water compartment of the engine, would tend to drive the water 20 out of the passage 14, but owing to the cavity 16 which extends a considerable distance on each side of said passage, water will collect therein below the vanes 13; and said vanes with air and water between them 25 will force the water in said compartment past said passage with such a velocity as to greatly lessen any tendency of the air to drive the water back out of the passage 14. The air being admitted to the pipe 8 from 30 the water compartment, and from the exhaust pipe 7, will expand therein according to its pressure, and according to the head of water in said pipe 8 above the valve 9, and tend to seat the same. If the supply 35 of air in the pipe 2 is continuous, water will continue to be forced past the valve 9, and air will continuously be forced in behind the water until the total head of water in the pipe 9 just balances the air pressure. 40 This head of water will be, of course, about 32 feet for each 15 pounds pressure of air, but since this head of water will be broken up into sections, in the manner well known, with columns of air between each section, it 45 is evident that the top section of water will reach to a height depending upon the total quantity of air in the air columns below. It is, also, evident that by simply increasing the quantity of air relative to the quantity 50 of water in said pipe 8, that the water may be raised to any height desired without increasing the air pressure. I have provided the valve 20 in the pipe 7 to regulate the amount of air that enters the pipe 8 above 55 the valve 9, and therefore to regulate in a measure the height to which the water may be forced, with a given pressure of air. That is to say, suppose the pressure in pipe 2 remains at 15 pounds to the square inch, 60 and the valve 20 be partially closed, the engine would slow down and less water would be forced past the valve 9. More air, however, would leak past the diaphragm 12, and proportionately more air to water would 65 enter the pipe 8, thereby lifting the water to

a greater height at the same pressure, although of course the total quantity of water lifted would remain the same, or 32 feet.

As above stated, mine waters carry acids which corrode the parts; sand which cuts the parts; slimes which clog and impede the operation of the parts; and in producing a practical pump it is necessary to provide against all these objections. By making the rotor of the simple construction shown, it 70 can be cast out of metal; and since the parts are designed to have a loose fit, the same may be enameled or otherwise rendered inert to acids. Or, of course, the parts may be suitably formed out of any suitable acid resisting material. The bearings being heavy 75 the mine waters serve to lubricate the same, and all parts may be cut by sand without changing the operation in the least.

In order to provide against clogging, and 80 to be able to lift the water to different levels at will, I have provided the usual strainer 25 over the passage 14, and have also provided a series of connections 26 between the pipes 2 and 8, each having a check valve 27, 90 28 or 29 as shown. The valve 27 is heavier than the valve 28, and the latter is heavier than the valve 29, as indicated by the decreasing sizes of the outer casings in Fig. 1. Or, of course, these valves may be all alike 95 but loaded by springs, or otherwise, so as to lift at different pressures. In order to render the action of these valves clear, I will suppose the pipe 8 to be 1,000 feet high and to be filled with alternate air and water 100 columns as in the Pohle pump, and also that the valve 3 is closed with 15 pounds pressure in pipe 2. In such condition, the total columns of water in pipe 8 will be 32 feet; the total columns of air will be 968 feet; and the 105 system will be in equilibrium with 15 pounds pressure on the valve 9, if we disregard the leakage back through the air engine, all as will be readily understood. If 110 while the system is balanced, as above described, however, we should admit air under pressure through the valve 27, it would press down as well as up; and while the system below said valve would remain undisturbed the material above would be subjected to the full pressure admitted through said valve; and if said pressure is sufficient, the contents of the pipe above said valve would be blown out, thereby lessening the pressure on the valve 9 by an amount equal 115 to the weight of the material thus discharged. In the same way, pressure admitted through the valve 28 would blow out of the pipe 8 any material above itself, and likewise still further lessen the pressure on the valve 9; and the same would be true of any other valve, as 29 located lower down, until finally there would be no pressure on the valve 9 except the small head of water 120 below the upper end of pipe 7. Now let 125

us suppose that the valve 3 is partially open with 15 pounds pressure in pipe 2; that the valve 29 requires say one pound of extra pressure to open it, the valve 28 two pounds, and the valve 27 say four pounds, and that the pump begins to clog or to slow down by reason of the discharge pipe 8 having been lengthened in order to send water to a higher level, or by reason of the slimy or viscous nature of the liquid or from other causes. If we open the valve 3 until 16 pounds pressure is in the pipe 2, instead of 15 pounds as before, the valve 29 will lift, and thereby increase the amount of air fed to the column, so that more air as well as more power is furnished to more rapidly discharge the material. If 16 pounds is not sufficient, then opening the valve 3 still further will put on say one more pound when the valve 28 will lift and furnish still more air in proportion to the liquid and still more power; while an increase of the pressure to 20 pounds would cause all three valves to open, and to still further increase the proportion of air to water in pipe 8 and to supply still more power to discharge said pipe. Of course, the discharge having been once established at a certain rate, the system is kept unbalanced by the operation of the air supplies through one or more of the valves 27, 28 or 29, and the discharge will continue so long as the lower air supply through pipe 7 remains insufficient to clear the pipe 8. While lifting water to any height, should the drills draw off so much air through the pipe 4 to prevent the water from being discharged through pipe 8, it is only necessary to open valve 3 to restore the pressure in pipe 2; and should it be desired at any time to lift the water to a greater height without increasing the pressure, or to lift the water to the same height after the pressure has fallen too low, it is only necessary to open the valve 20 and thereby increase the proportion of air to water that enters pipe 8, all as will be readily understood.

The modification of my invention disclosed in Fig. 4, is especially adapted to very shallow sumps, or to those conditions that often exist in mines where it is inconvenient to get large reservoirs of water to draw from, although the running supply may be great. In this figure the pipe or hose 30 is joined to the opening 14, and a pipe or hose 31 is provided into which the nozzle 32 projects, as shown. Said nozzle is connected with the main air pipe 2, by the pipe or hose 33, provided with a controlling valve 34. The injector action of the nozzle 32, combined with the suction and forcing action of the rotor 13, forces the water past the valve 9, when the other principles above disclosed come into play.

In Fig. 6, I have shown a form of air

engine and water lifter which is useful in slimes and waters carrying a great deal of sand. In this figure the air engine operates a screw 36, which forces the water into the pipe 8 and past a check valve not shown. Air escaping past the diaphragm 12 follows the water up into the pipe 8, and aids in lifting the same as in the other forms.

In all these forms it will be observed that either a continuous source of compressed air, or an intermittent source may be employed. No suction from the compressor is required, and therefore the time which would be lost in raising, lowering and reversing the pressure in pipe 2 is saved. Furthermore, by simply opening and closing the valve 3 at regular intervals by any suitable and well known means, the constant pressure supplied to pipe 2 may be rendered intermittent, and an amount of work may be obtained from the air almost equal to that demanded by theory. My invention, however, is not limited to a source of pressure devoid of suction, and I have illustrated in Fig. 5, a further modification in which suction is applied from the compressor itself. In this figure, 40 represents any suitable compressing and suction device, here shown conventionally as of a reciprocating piston type; 41 and 42 the air pipes; 43 the water discharge pipe; 44 and 45 the water receiving chambers into which said pipes lead; and 46 and 47, pipes or hose connections leading from said chambers to an open ended pipe or hose 48, adapted to enter the sump or other reservoir from which water is to be discharged. Nozzles 49 and 50 enter the open ends of said pipe 48, and are connected respectively to the air pipes 41 and 42, by the hose or pipe connections 51 and 52, as shown. Suitable check valves 53 and 54 control respectively the said connections 51 and 52, suitable check valves 55 and 56 respectively control the upper ends of pipes 46 and 47, and like valves 57 and 58 respectively control the exits from the water receiving chambers 44 and 45, as illustrated. Between the air pipes 41 and 42 and the water delivery pipe 43 are a plurality of connections, as shown, in which are located check valves 61, 62, 63 and 64, each requiring less pressure to lift them, as indicated by their diminishing size as one goes downward. These valves may be of any suitable construction, and one form is illustrated in detail in Fig. 2. The operation of this form of my invention is as follows:—A suction being created by the apparatus 40, in say pipe 42, and a pressure in pipe 41, more or less water will be sucked into the pipe 48, the pipe 47, the water chamber 45, and the said pipe 42. And the suction action will be aided by the injector action of the air forced through the nozzle 49 from the pipe 41. Upon a pressure being

now applied to said pipe 42, and a suction to the pipe 41, any water that has already passed the valve 56 will now cause said valve to be closed; and the water in chamber 45 will be forced past the valve 58. Any air that escapes past the valve 54 will pass through the nozzle 50, and by its injector action tend to force the water past the valve 55 into the chamber 44. The suction in said chamber will likewise tend to cause the water to enter the same, as well as the pipe 41. Upon pressure being again applied to pipe 41, and suction to pipe 42, the first set of operations will be repeated and the water in chamber 44 be forced past the valve 57. As the pump continues to operate, water will rise in the pipe 43 above the valves 57 and 58, until it gets above the check valves 64, which require very little pressure to lift them. When the head of water passes the valves 64, the air escaping past said valves will cut off a portion of said head and lift the same a distance proportional to the quantity that escapes, proportional to the pressure at which it escapes, and proportional to the amount or weight of the water piston thus cut off, all as is well understood. That is to say, it is now well known that air injected into a rising column of water, in the manner indicated, will form alternate pistons or columns of water and air in the pipe 43, that the total height of the water pistons will be 32 feet for each 15 pounds pressure of the air, and that the total height of the air columns or pistons will depend upon the amount of air admitted to the pipe 43, and that this amount will again depend upon the pressure at which the air is admitted in the first instance. By suitably adjusting the valves 53 and 54, the amount of air that follows the water up past the valves 57 and 58 may be controlled, and by adjusting the valves 64, the amount of air that cuts off the rising column into pistons may be likewise controlled; while suitably adjusting both of these valves controls the relative amount of air and water in the pipe 43, and therefore the height to which any given weight of water will be lifted with a given pressure in the pipes 41 and 42, all as will be readily understood by those skilled in this art. When it is desired to lift the water to greater heights without disturbing the compressor, the valves 66 in the pipes 41 and 42 are opened sufficiently to increase the pressure enough to lift one or more of the valves 63, 62 or 61. And the same thing is done when it is desired to blow out the pipes at any time, or to deliver a greater volume of water in a less time, all as disclosed above.

In all cases it will be observed that none of the parts need fit tightly, and therefore they may be cast out of metal and enamelled to avoid the action of mine waters; nor

does the cutting of the parts by sand make any difference in the operation; nor the shallowness of the water so long as a pipe of moderate diameter may be immersed therein. In addition to the above, by the simple manipulation of one or more valves controlling the air pipes, the pump may be made to work faster; to throw water to various heights, at will; or the slowing down effect of air drills when using the same air supply may be avoided.

Since various changes may be made by those skilled in the art without departing from the spirit of my invention, I do not wish to be limited to the exact details disclosed, except as pointed out in the claims.

What I claim is:—

1. In a compressed air water elevator, the combination of an air pipe; a casing provided with a plurality of chambers connected to said pipe; means by which air under pressure may be admitted to one of said chambers and allowed to leak into the other; a water delivery pipe; and a connection between said air pipe and water delivery pipe above said chamber, substantially as described.

2. In a compressed air water elevator, the combination of a plurality of chambers into which air may be delivered successively and simultaneously and from one of which water may be expelled; an air pipe connected to said chambers; a water delivery pipe connected to said chamber; a check valve between said water pipe and one of said chambers; and a connection between said water and air pipes above said check valve, substantially as described.

3. In a compressed air water elevator, the combination of a plurality of chambers into which air is delivered successively and simultaneously and from one of which water may be expelled; an air pipe connected to said chambers; a water delivery pipe connected to said chambers; a check valve between said water pipe and one of said chambers; a plurality of connections between said water and air pipes above said check valve; and a plurality of check valves in said connections, each adapted to lift at a different pressure, substantially as described.

4. In a compressed air water elevator, the combination of a plurality of chambers; an air pipe adapted to successively and simultaneously deliver air under pressure into said chambers, while expelling water from one of the same; a water pipe; a check valve in the same above said chambers; a connection from one of said chambers leading into the water to be lifted; a pipe between said connection and said air pipe adapted to deliver air into said connection below said chambers; and a connection between said air and water pipes above said check valve, substantially as described.

5. In a compressed air water elevator, the combination of a plurality of chambers; an air pipe leading to said chambers adapted to deliver air under pressure into both of 5 said chambers, while expelling water from one of the same; a water pipe; a check valve in the same above said chambers; a connection from one of said chambers leading into the water to be lifted; a valved pipe between 10 said connection and said air pipe adapted to deliver air into said connection below said chambers; and a valved connection between said air and water pipes above said check valve, substantially as described. 15
6. In a compressed air water elevator, the combination of an air engine having an air compartment and a water compartment; suitable rotors in said compartments separated by a partition permitting air to leak 20 from the one compartment to the other; an air pipe leading to said air compartment; a water pipe leading from said water compartment; and a pipe connecting said air compartment and said water pipe, substantially 25 as described.
7. In a compressed air water elevator, the combination of an air engine having an air compartment and a water compartment; suitable rotors in said compartments separated by a partition permitting air to leak 30 from the one compartment to the other; an air pipe connecting with said air compartment; a valve in said pipe; a water pipe leading from said water compartment; a check valve in said water pipe above said 35 water compartment; and a valved pipe connecting said air compartment and said water pipe, substantially as described.
8. In a compressed air water elevator, the combination of an air engine having an air compartment and a water compartment; suitable rotors in said compartments sepa- 40
- rated by a partition permitting air to leak from the one compartment to the other; an air pipe connecting with said air compartment; a water pipe leading from said water compartment; a plurality of connections between said water and air pipes; a plurality of check valves each adapted to be lifted by a different pressure in said connections; and a valved pipe connecting said air compartment and said water pipe, substantially as 45 described. 50
9. In a compressed air water elevator, the combination of an air pipe; a casing provided with an air chamber connected with said pipe; and a water chamber connected with the air chamber; means by which air under pressure may be admitted to both of said chambers at the same time; a water delivery pipe; a connection between said air pipe and water delivery pipe above said chambers; a pipe 31 connected to said water chamber; and a connection 33 between said air pipe and said pipe 31, substantially as 55 described. 60
10. In a compressed air water elevator, the combination of a plurality of chambers into which air may be delivered at the same time and from one of which water may be expelled; an air pipe connecting with said chambers; a water delivery pipe connected to said chambers; a check valve between said water pipe and one of said chambers; pipes 30 and 31 connecting said water chamber with a water supply; and a valve pipe 33 connecting said air pipe and said pipe 31, substantially as described. 70

In testimony whereof, I affix my signature, in presence of two witnesses.
